CLAIM

We claim the ornamental design for a tooth brush holder, as shown and described.

DESCRIPTION

FIG. 1 is a right view of a tooth brush holder showing our new design;

FIG. 2 is a left view thereof;

FIG. 3 is a bottom view thereof;

FIG. 4 is a top view thereof;

FIG. 5 is a front view thereof;

FIG. 6 is a rear view thereof; and,

FIG. 7 is a right, front, and top perspective view thereof.

All features illustrated in phantom or broken lines are expressly disclaimed and form no part of the claimed design.
